UNITED STATES PATENT OFFICE.

LEWIS M. ELLIS, OF DETROIT, MICHIGAN, ASSIGNOR TO ELLIS ENGINE COMPANY, OF DETROIT, MICHIGAN, A CORPORATION OF MICHIGAN.

CARBURETING APPARATUS.

1,022,664.

Specification of Letters Patent. Patented Apr. 9, 1912.

Application filed January 7, 1911. Serial No. 601,424.

To all whom it may concern:

Be it known that I, LEWIS M. ELLIS, a citizen of the United States, residing at Detroit, county of Wayne, State of Michigan, have invented a certain new and useful Improvement in Carbureting Apparatus, and declare the following to be a full, clear, and exact description of the same, such as will enable others skilled in the art to which it pertains to make and use the same, reference being had to the accompanying drawings, which form a part of this specification.

My invention relates to carbureting apparatus for internal combustion engines, and an object of my improvements is to provide an improved apparatus for supplying fuel to a two-cycle internal combustion engine. I accomplish this object in the device illustrated in the accompanying drawings, in which—

Figure 1, is a sectional elevation of a two-cycle engine and the apparatus embodying my invention attached to said engine. Fig. 2, is a detail plan sectional view on the line 2—2 of Fig. 1.

A, is a cylinder, B, a crank case, C a piston, D, the crank and E, the connecting rod of a two-cycle internal combustion engine.

F, is the by-pass, or passage which connects the compressed air from the crank case to the port to the combustion chamber of the engine.

G, is the port connecting the combustion chamber with the upper end of the by-pass, or passage F.

I^r, is an intake port adapted to be uncovered by the piston at the upper end of its stroke to admit air to the crank case of the eng.

H, is a chamber cored out around the port G.

H', is a small passage, in the wall of the cylinder, connecting the chamber H with the combustion chamber of the engine.

h, is a drain port at the bottom of the chamber H adapted to carry away any oil that may be thrown into said chamber.

The particular form of the chamber H is not material so long as it is in the iron adjacent to the intake ports: In the drawing it is shown in Fig. 1 above and below said ports and there are connecting passages shown in Fig. 2 on each side of the port G.

i, is a puppet valve, at the upper end of

the passage F, controlling the opening between said passage and the port G.

J, is a throttle valve adapted to control the opening into the port G. The port G has three passages marked G, G¹ and G² in Fig. 2, and there are openings g, g¹ and g² opening respectively into said passages. The throttle valve J is provided with parts or portions J¹ and J² shaped in the form of portions of the wall of a hollow cylinder, fitting into a cylindrical chamber into which the port G opens and large enough to cover any one of the ports g, g¹, g². In the position of the throttle valve shown in Fig. 2, all of the ports are open and the engine will be at full power. If the throttle valve is turned until the part J² covers the passage g only the ports g¹, g² will be open and the engine will have less power. If the throttle valve is turned so that the portion J² closes the port g² part way and the portion J¹ covers the port g¹ part way, the engine will have still less power as the openings from the passage F to the combustion chamber are throttled.

L, is a conduit for the hydrocarbon, opening at the seat of the valve I so that when said valve is raised the conduit will be open and when said valve is seated it will be closed.

M, is a needle valve controlling the area of the opening to the conduit L.

N, is a supply pipe for the hydrocarbon.

P, is a reservoir for the hydrocarbon. The pipe N leads from the bottom of the reservoir P to a chamber opening into the conduit L.

p, is a glass cylinder forming in connection with its metal ends the reservoir P. The glass p enables one to observe the level of the fluid in the reservoir P.

q, is a valve operated by the float Q to check the inflow of fluid when the fluid is at a certain level in the reservoir P.

S, is a supply pipe for the hydro-carbon fluid.

s, is an automatic non-return valve opening toward the reservoir P.

R, is a pipe opening into the top of the reservoir P at P² and into the cylinder A, near the lower end of said cylinder, at the point marked R¹. The opening at R¹ to the pipe R is closed by the piston C when the inlet port G is open.

The operation of the above described device is as follows:—When the piston C rises, it first covers the inlet port G and the exhaust port E^x and then the opening H¹, and uncovers the opening to the pipe R at R¹. As the piston C rises, it draws a partial vacuum in the crank case which draws air from the reservoir P and causes an inflow of hydrocarbon from the supply pipe S to said reservoir, unless the valve q is closed. At the upper end of the stroke of the piston C the explosion takes place in the combustion chamber driving the piston C down, uncovering the opening H¹ just before the exhaust port E^x is opened, and permitting the hot gases to flow into the chamber H to heat the walls of the inlet port G. As the piston C further descends it opens the exhaust port E^x discharging the products of combustion and then the inlet port G in the usual way. During the down stroke of the piston C air has been compressed in the crank chamber and when the port G is uncovered the air passes through the passage F and port G to the combustion chamber being supplied with fuel as it passes the valve I which latter is raised by the air uncovering the mouth of the conduit L. During the greater portion of the down stroke compression takes place in the crank case and its pressure passes through the pipe R into the reservoir P. When the piston C covers the opening at R¹ to the pipe, or passage R, the connection between said reservoir and the crank case is closed and the pressure is held in the reservoir forcing the hydrocarbon from said reservoir through the pipe N and conduit L to the seat of the valve where it is mingled with the air passing to the combustion chamber. The pressure is held constant in the reservoir P while the air is being passed through the passage F and port G. The chamber H keeps the walls of the port G hot and assists to vaporize the fuel. The weight of the valve I is sufficient to prevent the inflow of fluid from the conduit L even when there is a maximum pressure in said reservoir.

What I claim is:—

1. In a two cycle internal combustion engine, the combination of a cylinder having a combustion chamber, a compression chamber, means for compressing air in said compression chamber, and transferring the same to the combustion chamber, a reservoir for liquid fuel, a conduit for said liquid lead-

ing to said engine, a passage connecting said reservoir above the liquid therein, and said compression chamber, and means for closing said passage during the time the air is being transferred from the compression chamber to the combustion chamber, as and for the purpose described.

2. In a two cycle internal combustion engine, the combination of a cylinder, a compression chamber, a piston adapted to reciprocate in said cylinder to compress air in said compression chamber, a passage for conveying the compressed air to the combustion chamber, a reservoir for fluid hydrocarbon, a conduit for said hydrocarbon communicating with said reservoir and with the passage for compressed air and a passage communicating with said reservoir above the fluid level therein, and opening through the wall of said cylinder at a point that shall be covered by the piston toward the lower end of its stroke, for the purpose described.

3. In a two cycle internal combustion engine, the combination of a cylinder, a compression chamber, a piston adapted to reciprocate in said cylinder to compress air in said compression chamber, a passage for conveying the compressed air to the combustion chamber, a reservoir for fluid hydrocarbon, a conduit for said hydrocarbon communicating with said reservoir and with the passage for compressed air and a passage communicating with said reservoir above the fluid level therein, and opening through the wall of said cylinder at a point that shall be covered by the piston toward the lower end of its stroke, a supply pipe leading to said reservoir, and an automatic valve in said supply pipe opening toward said reservoir, for the purpose described.

4. In an internal combustion engine, the combination of a working cylinder, an intake port, an inclosed chamber adjacent to said inlet port, said cylinder being provided with an opening through its wall communicating with said chamber, said opening being so located that it shall be in communication with said cylinder before the exhaust port is opened.

In testimony whereof, I sign this specification in the presence of two witnesses.

LEWIS M. ELLIS.
